UNITED STATES PATENT OFFICE.

FREDERICK S. TEW, OF FORT WORTH, TEXAS.

DESIGN FOR A WINDSHIELD.

55,897.

Specification for Design.

Patented July 20, 1920.

Application filed February 19, 1920. Serial No. 359,937. Term of patent 3½ years.

To all whom it may concern:

Be it known that I, FREDERICK S. TEW, a citizen of the United States, residing at Fort Worth, in the county of Tarrant and State of Texas, have invented a new, original, and ornamental Design for Windshields, of which the following is a specification, reference being had to the accompanying drawing, forming part thereof.

The figure is a perspective view of a windshield, showing my new design.

I claim:

The ornamental design for a windshield, as shown.

FREDERICK S. TEW.

Witness:

CHAS. E. BOWEN.
